UNITED STATES PATENT OFFICE.

CARL L. SHELTON, OF GREENFIELD, TENNESSEE.

TAG OR CHECK.

1,324,568.

Specification of Letters Patent. Patented Dec. 9, 1919.

Application filed February 10, 1919. Serial No. 276,081.

To all whom it may concern:

Be it known that I, CARL L. SHELTON, a citizen of the United States, residing at Greenfield, in the county of Weakley and State of Tennessee, have invented a new and useful Improvement in Tags or Checks, of which the following is a specification.

This invention relates particularly to tags or checks adapted to be applied to various articles by means of some suitable attaching device; and the primary object of the invention is to provide a stringless tag or check, which is suitably strong and durable, and which can be applied, with great facility, to an article, and which can be removed, when desired, without injury to the tag or check.

The invention is illustrated in its preferred embodiment in the accompanying drawing, in which—

0 Figure 1 represents a plan view of a tag or check constructed in accordance with the invention; Fig. 2, a similar view, showing the device with the tab-portion folded upon itself and interlocked with the body-portion; Fig. 3, a view of the obverse side of the check in the form shown in Fig. 2; Fig. 4, a sectional view taken as indicated at line 4 of Fig. 3; Fig. 5, a view of the modification of the improved tag or check; Fig. 6, a view of the obverse side of the same, showing the tab folded and its free end secured to the body-portion; and Fig. 7, a broken edge view of the form shown in Fig. 6.

5 Referring to Figs. 1 to 4, inclusive, A represents the body of a tag or check which has formed integrally at one end thereof an elongated tab A'. The body-portion A is provided, a short distance from the line of junction with the base of the tab A', with a transverse slot 1, of suitable dimensions to enable the free end-portion of the tab to be inserted therethrough. The tab is provided near its free extremity with a small interlock-member, or catch-member, 2. This is formed by making a U-shaped incision in the material of the tab, the material being left intact at the point 2*. Thus, the member 2 is in the form of a very small interlock tab, which may be bent out of the plane of the attaching tab A'. The corners of the tab A', at the free end of the tab, are cut away, as indicated at 3.

In the illustration given, the tag or check is shown provided on one side with a name-blank 4, and with blanks 5, 6, and 7, asso-

ciated with words or characters indicating the nature of the data to be inserted in said blanks. The tag is also provided with a number, or other identifying character, 8, 60 and has a detachable portion provided with an identical number, or character, 8*. The tag described is well adapted for use, in a small form, as a watch-check, or for analogous purpose. It also might be used in this 65 form as a chicken tag, or for some such purpose.

In attaching the tag, the tab A' is bent to form a loop, and the end of the tab is inserted through the slot 1, the retaining tab, 70 or catch, 2, being brought into interlocking engagement with the opposite side of the body of the tag, above the slot 1, as clearly appears from Figs. 3 and 4.

In the modification shown in Figs. 5, 6 75 and 7, B represents the bdy of the tag or check, and B' represents the attaching tab formed integrally with one end thereof. In this case, the body B is provided near one end with a metal eyelet 9; and the end-portion of the tab B' is equipped with a metal clip 10 having flexible members 10^a which may be passed through the eyelet 9 and bent or clenched on the opposite side, 80 as shown in Figs. 6 and 7. The clip 10 may 85 be provided with integral brads 10^b, which may be inserted through the end-portion of the tag B' and clenched on the opposite side. This form of device is somewhat more expensive than the first described form, but is 90 a practicable form, and may be desirable, especially in the case of the larger sized tags.

It is desirable to form the tag, or check, and the attaching tab, which is integral therewith, of tough and somewhat stiff paper, or 95 the like. Thus, the device may be conveniently formed of a heavy linen paper, or from a paper having a woven fabric therein; or any suitable expedient may be adopted in the manufacture of the paper for the 100 purpose of rendering it tough, somewhat pliable, but suitably stiff for tag or check purposes. If desired, a reinforced light card-board may be employed.

The improved device can be manufactured 105 cheaply, is capable of being easily applied to an article, and may be removed, without destruction of the device, when desired.

The foregoing detailed description has been given for clearness of understanding 110 only, and no unnecessary limitation should be understood therefrom, but the appended

claim should be construed as broadly as permissible, in view of the prior art.

What I regard as new, and desire to secure by Letters Patent, is:

5 A device of the character set forth comprising a body-portion and a main elongated tab formed integrally with one end of said body-portion, said body-portion having a transverse slot near the base end of said

tab, said tab having in its free end-portion 10 a small interlock-tab formed by a substantially U-shape incision in the main tab, the interlock-tab being adapted to lie in the plane of the main tab during insertion through said slot and to project from a 15 side surface of the main tab to effect the interlock.

CARL L. SHELTON.
